Primary Examiner — Martie K Holtje(74) *Attorney, Agent, or Firm* — Hedman & Costigan, P.C.; James V. Costigan; Kathleen A. Costigan(57) **CLAIM**

The ornamental design for a wristwatch case, as shown and described.

DESCRIPTION

FIG. 1 is a front perspective view of a wristwatch case according to the present invention;

FIG. 2 is a front view thereof;

FIG. 3 is a rear view thereof;

FIG. 4 is a right side elevational view thereof;

FIG. 5 is a left side elevational view thereof; and,

FIG. 6 is a top plan view, the bottom plan view being a mirror image thereof.

The watch hands depicted by broken lines in FIGS. 1 and 2 have been shown for the purpose of illustrating portions of the wristwatch case that form no part of the claimed design.
